UNITED STATES PATENT OFFICE.

MATTHEW O. TROY, OF SCHENECTADY, NEW YORK, ASSIGNOR TO GENERAL ELECTRIC COMPANY, A CORPORATION OF NEW YORK.

TRANSFORMER.

1,008,623.

Specification of Letters Patent. Patented Nov. 14, 1911.

Application filed February 2, 1911. Serial No. 606,078.

To all whom it may concern:

Be it known that I, MATTHEW O. TROY, a citizen of the United States, residing at Schenectady, county of Schenectady, State 5 of New York, have invented certain new and useful Improvements in Transformers, of which the following is a specification.

My invention relates to electric transformers, and its object is an improved form of 10 construction for such apparatus.

I have illustrated and described my invention as applied to transformers of the type shown in Patent No. 861,029, W. A. Hall, though it is not limited in its application to 15 this type of transformer. Such transformers, as previously constructed, have consisted of a casing or tank inclosing the transformer core and winding and partially filled with oil for insulating and cooling the same. 20 Fastened in any suitable manner to the transformer structure is a terminal board to which are led the terminals of the transformer winding and the conductors leading outside the transformer casing. This terminal board in the past has been arranged 25 so that it will be above the oil which only partially fills the transformer casing. I have found that if this terminal board be submerged in the oil, lightning or high potential surges do less injury to the transformer, 30 and further that the transformer structure may be rendered more compact. If, however, this terminal board be placed adjacent to the transformer core and winding, unless 35 special precautions are taken, the circulation of oil in the transformer would be impaired and the full effects of oil cooling would not be obtained.

The object of my invention then is the construction of a special terminal board which may be submerged in the oil in a plane above the windings and the core closely adjacent to the transformer structure and interfering to a minimum degree with the oil circulation.

45 I accomplish the object of my invention by providing the terminal board with a large hole or aperture which for the special type of transformer which I have illustrated is substantially above the central leg of the 50 transformer core, thereby permitting a free circulation of the oil in the transformer casing.

For a further understanding of my inven-

tion, reference may be had to the accompanying drawings, where—

Figure 1 is a vertical view, partly in section, of a transformer showing my improved terminal board; and Fig. 2 is a top view of the transformer shown in Fig. 1, with the cover removed.

Referring first to Fig. 1, the casing 1, provided with a suitable cover, contains the transformer core 2 and windings 3, these being submerged in oil, or other suitable insulating fluid, which fills the transformer casing to the level shown by the dotted line. Placed beneath this level, or submerged in the oil, is the terminal board 4 which is in close proximity to the core and has an aperture or hole substantially in its center. The core, as may be seen from an inspection of the figures, consists of a central leg or member 5 and external legs 6 the central leg being surrounded by windings 3. The usual ventilating spaces between the windings, and the windings and the core, may be provided, and I have not deemed it necessary to illustrate such.

The principle upon which my invention works is as follows: When the transformer 80 is operating, the central leg of the transformer core, with the surrounding windings, will be the hottest portion of the structure. The oil in the vicinity of these portions will become more highly heated than that adjacent to the other portions of the transformer core and windings, and, owing to the difference in weight between the hotter and the cooler oil, a circulation will be set up, as shown by the arrows in Fig. 1. The heated 85 oil will tend to rise through the spaces between the transformer windings and through the spaces between the windings and the core and will pass up through the hole or aperture in the terminal board and thence flow 90 downward adjacent to the sides of the transformer casing. It will be seen then that with my improved form of terminal board a free circulation of the oil or insulating fluid is obtained in the transformer structure.

While I have described a preferred embodiment of my invention as applied to a transformer having central and external legs, I do not limit myself to the embodiment which I have described and seek in the appended claims to cover all embodiments

which will be obvious to those skilled in the art and not depart from the spirit of my invention.

What I claim as new and desire to secure 5 by Letters Patent of the United States, is,—

1. A transformer comprising in combination an inclosing casing, an insulating fluid in said casing, a core in said fluid, windings surrounding said core, and a terminal board 10 for the windings submerged in said fluid in a plane above the windings and the core having an aperture permitting a free circulation of said fluid.

2. A transformer comprising in combination 15 an inclosing casing, an insulating fluid

in said casing, a core in said fluid having central and external legs, windings surrounding a portion of said core, and a terminal board for the windings submerged in said fluid above the windings and core having an aperture substantially above the central core leg permitting a free circulation of 20 said fluid.

In witness whereof, I have hereunto set my hand this 31st day of January, 1911.

MATTHEW O. TROY.
